[57] CLAIM

The ornamental design for the electronic instrument
housing, substantially as shown and described.

DESCRIPTION

FIG. 1 is a top plan view of the instrument housing
showing my new design;

FIG. 2 is an end view of the instrument housing shown
in FIG. 1;

FIG. 3 is a bottom plan view of the instrument housing
of FIGS. 1-2;

FIG. 4 is a side elevational view of the instrument hous-
ing of FIGS. 1-3; and

FIG. 5 is a cross-sectional view taken through FIG. 1
along the line 5—5 on an enlarged scale.

*Fig.1.**Fig.4.**Fig.2.**Fig.5.**Fig.3.*
